UNITED STATES PATENT OFFICE.

HARRY B. ARDEN, OF NEW YORK, N. Y.

DIGGING APPARATUS.

No. 854,395.

Specification of Letters Patent.

Patented May 21, 1907.

Application filed February 3, 1906. Serial No. 299,242.

To all whom it may concern:

Be it known that I, HARRY B. ARDEN, a citizen of the United States, and a resident of the city, county, and State of New York, have invented new and useful Improvements 5 in Digging Apparatus, of which the following is a specification.

The object of my invention is to provide an apparatus of this class which will always 10 carry away and dispose of all earth or dirt disturbed by an excavator, and do this regardless of the speed with which the excavator is operated or the particular part of the cut wherein it is located. In the embodiment 15 of my invention which accomplishes this object, the shovel or excavator is suitably mounted and connected with a conveyer of a peculiar type as will hereinafter appear. There are also certain improvements in de- 20 tails of construction incidental to the main invention as will also hereinafter appear.

For a more particular description of my invention, reference is to be had to the accompanying drawings forming a part hereof in 25 which:

Figure 1 is a side elevation of one form of my apparatus. Fig. 2 is a section through the conveyer showing the manner of supporting and connecting the buckets. Fig. 3 is a 30 plan view of the hopper. Fig. 4 is a perspective view of one bucket.

Throughout the various views of the drawings similar reference characters designate similar parts. The various features of my 35 invention may be embodied in many forms, differing somewhat in details, but all having features in common.

In the modification shown in Figs. 1 to 4 inclusive, the steam shovel 1 is shown 40 mounted on a frame 2, which is connected with a conveyer 3, all of which move as a unit, being carried by suitable trucks 1^a on a transverse frame 4 carried by trucks on the longitudinal tracks 5 and 6, the other end of 45 the conveyer 3 being supported by a pier 7 mounted on a truck 8 which runs on a transverse frame 9 supported by two trucks 10 and 11 which in turn run on tracks 12 and 13 placed parallel to the tracks 5 & 6, but on the 50 bank instead of in the cut 14. The conveyer 3 and frame 2 are flexibly connected by any suitable means, such as a pin and slot connection 65. The soil or earth excavated by the shovel 1 is carried by the conveyer to its 55 upper end and there dumped on the spoil pile A. As the conveyer 3 and shovel 1 are di-

rectly connected; they always have the same relative positions with regard to transverse and longitudinal movements, with the result that each is always ready to co-operate with 60 the other.

From the foregoing a general idea of my invention will be readily had. The details are for the most part of the conventional type and so only the novel features need be 65 particularly pointed out.

The steam shovel 1 may be of any desired form and is no part of my invention.

Conveniently located at the lower end of the conveyer 3 is a hopper or trough 15 which 70 is situated so that the shovel 1 may dump into it. This hopper 15 has flaring sides 16, 17 and 18 and is open at its bottom and upper end and slightly narrower through this bottom than the cars or buckets 19 which 75 pass beneath it. This hopper 15 is suitably and rigidly supported from the frame of the conveyer 3 and has sufficient clearance over the buckets 19, but not sufficient to allow the dirt excavated to drop through. 80

The buckets 19 have a bottom 20 with a rear vertical wall 21 and two side walls 22 and 23, but no front wall. Each bucket has also three spindle lugs, the rear lower edge having the lugs 24 and 25 and the front edge 85 having the lug 26. These spindle lugs are so proportioned and arranged that the lug 26 of each bucket is between the lugs 24 and 25 of the bucket immediately in front and a common spindle unites the three. At each end 90 of each spindle are loose flanged wheels 27 that run on tracks 28 and 29 above and below the axis of conveyer 3. By this means the buckets 19 are united unto an endless chain with flanged wheels supporting the 95 same at each end of each link so that the chain may always move without delay or friction. As the buckets have no front wall they may be easily dumped. Motion is imparted to this endless chain by means of 100 sprocket wheels 30 and 31 at each end of the conveyer which are rotated by any suitable means (not shown). The vertical walls of the buckets 19 come sufficiently close together to form practically continuous side 105 walls until the chain is bent at one of the pairs of sprocket wheels at either end of the conveyer.

The bracing given to the conveyer depends upon its size, length and shape. It 110 may be given any suitable form and is not necessarily straight, but as such details are

well within the skill of an engineer, it is not necessary to consider them here. Generally it is better to place a pivot 32 between the pier 7 and truck 8 to allow for inequalities in the tracks 12 and 13. If these tracks are nearly or perfectly true this pivot 32 may be dispensed with.

From the foregoing the operation of this embodiment of my invention will be readily understood. The shovel 1 from time to time and as rapidly as possible empties into the hopper 15 and the spoil passes into the buckets 19 which run along the conveyer 3 and these buckets 19 are dumped when the bucket 15 passes over the sprocket wheels 31. At all times the conveyer is ready to receive spoil from the shovel 1, and no matter how rapidly this shovel 1 is operated, the same condition remains, so that the shovel is never delayed by the conveyer, a result never before obtained.

For some purposes it is essential to use the precise form of conveyer herein described. For others, different forms may be employed so that my invention in its broadest aspects is not to be considered as limited to the precise disclosure herein, but as broad enough to cover all structures that come within the scope of the annexed claims.

Having thus described my invention what I claim is:—

1. An excavator, means for mounting the

same so as to permit either transverse or longitudinal movement, and a conveyer connected with said excavator so as to partake of all its transverse and longitudinal movements. 35

2. An excavator, means for mounting the same so as to permit either transverse or longitudinal movements, a conveyer connected at one end to said excavator and having 40 its other supported by a transverse track mounted on longitudinal tracks through suitable trucks.

3. An excavator, tracks in a cut for supporting the same, a set of tracks on the bank, 45 a conveyer, one end of which is supported by the same means as the excavator and the other from said tracks on the bank.

4. An excavator, tracks in a cut for supporting the same, tracks on a bank, a conveyer supported at one end by the tracks in the cut and at the other by the tracks on the bank, and means for giving the excavator and conveyer the same transverse and longitudinal movements by which their relative positions remain unchanged and the conveyer is kept always ready to receive the material excavated by the excavator. 55

Signed this 30th, day of January, 1906.

HARRY B. ARDEN.
